UNITED STATES PATENT OFFICE.

CHARLES W. KIRSCH, OF THREE RIVERS, MICHIGAN, ASSIGNOR TO KIRSCH MANUFACTURING COMPANY, OF THREE RIVERS, MICHIGAN, A CORPORATION OF MICHIGAN.

CURTAIN-ROD.

964,653.

Specification of Letters Patent. Patented July 19, 1910.

Application filed December 7, 1908. Serial No. 466,271.

To all whom it may concern:

Be it known that I, CHARLES W. KIRSCH, citizen of the United States, residing at Three Rivers, in the county of St. Joseph 5 and State of Michigan, have invented certain new and useful Improvements in Curtain-Rods; and I do hereby declare the following to be a full, clear, and exact description of the invention, such as will enable 10 others skilled in the art to which it appertains to make and use the same.

My invention relates to a novel construction in a curtain rod, the object being to provide a simple, compact, easily adjustable, 15 strong and ornamental device of this character, and consists in the features of construction and combinations of parts hereinafter fully described and claimed.

In the accompanying drawings illustrating this invention: Figure —1— is a top plan view partly in section of a curtain rod constructed in accordance with my invention. Fig. —2— is a front elevation of the same. Fig. —3— is a fragmentary detail 25 view in elevation showing means employed for securing the telescopically interfitting members of the curtain rod against relative movement. Fig. —4— is a detail section on the line 4—4 of Fig. —3—.

My invention consists more particularly in certain details of construction of an adjustable curtain rod whereby the simplicity, convenience, and general appearance and adaptability of the rod are improved as will 30 be more particularly pointed out in the following.

The rod proper consists of flat members A and B made of strips of sheet metal, the side edges of which are bent over so that their 40 free edges are opposed to each other and providing opposed U-shaped grooves C adjacent the side edges of the strips, the strip B being of such smaller dimensions than the member A as to fit snugly telescopically 45 within the latter. Strips of this form are illustrated and described in Letters Patent No. 850089 granted to me April 9, 1907. This patent shows the rod curved at its ends.

In my present invention the rod is straight 50 and is secured at its ends to brackets D which I believe to be novel. Said brackets consist of opposed U-shaped plates, one flange of each abutting against the room face of the window casing and being there

secured, and the other flange extending parallel therewith. To the last named flanges the projections E are secured, the free ends of the latter being annularly reduced and threaded. The middle or web portions of the plates D are provided respectively with 60 openings F and recesses G to receive the end projections of shade rollers. The free end portions of the members A and B are provided with openings to receive said threaded ends of said projections and are secured 65 thereon by means of the rosette nuts H. The latter consist of round disks of sheet metal having central threaded opening, the central portions surrounding said opening being drawn to form cylindrical recesses I. 70 Substantially semi-spherical sheet metal caps J are then pressed into said recesses edge downward, thus hiding the threaded ends of the projections from view and rendering the nut very ornamental. Each of 75 said flanges may be provided with a plurality of said projections E to support a plurality of rods as illustrated. The shape of the brackets D may be varied to suit different tastes and meet different conditions. 80 The said openings F and recesses G may be so spaced as to permit a single shade roller supported therein to be adjusted to different positions or they may be spaced to accommodate a plurality of shade rollers. Thus 85 shades of different colors may be hung behind lace curtains and various color effects produced in the room.

In Figs. 3 and 4 I have illustrated means for fixing the relative positions of the members A and B relatively to each other to 90 make a curtain rod of fixed length.

The adjustability of the rod is of value only in primarily mounting the same to provide the proper length of rod. After the 95 brackets are mounted and the rod adjusted to fit it is desirable to maintain it at such fixed length. To accomplish this I provide a wedge L which is driven into the end of the member B within the member A and 100 slightly expands the former, whereby it becomes so firmly wedged in the latter as to be incapable of relative movement except upon exerting extraordinary strain.

I claim as my invention:

1. A device of the kind specified, comprising brackets secured to the window frame in opposed relation to each other,

105

2
said brackets being U-shaped, the middle portions thereof being provided respectively with openings and recesses to receive the end projections of a shade roller, one flange 5 of said brackets being secured to the window casing, projections on the free flanges of said brackets having reduced threaded free end portions, a curtain rod provided in its ends with openings to receive said 10 threaded end portions of said projections, and nuts engaging the latter to secure said curtain rod in place thereon.

2. A device of the kind specified, comprising brackets secured to the window casing on opposite sides thereof and provided at their free ends with flanges, projections on said flanges having reduced threaded free end portions, a curtain rod having openings in its end portions to receive said 15 threaded end portions of said projections, nuts engaging the latter to secure said rod in place thereon, the portions of said brackets lying between the points of attachment thereof to the casing and said flanges 20 being provided respectively with openings 25

and recesses to receive the end projections of shade rollers.

3. A device of the kind specified, comprising brackets secured to the window casing on opposite sides thereof and provided 30 at their free ends with flanges, projections on said flanges having reduced threaded free end portions, a telescopically adjustable curtain rod having openings in its end portions to receive said threaded end portions of said 35 projections, nuts engaging the latter to secure said rod, the portions of said brackets lying between the points of attachment thereof to the casing and said flanges being provided respectively with openings and recesses to receive the end projections of shade 40 rollers.

In testimony whereof I have signed my name in the presence of two subscribing witnesses.

CHARLES W. KIRSCHI.
